(57) **CLAIM**

The ornamental design for a wine glass holder, as shown and described.

DESCRIPTION

FIG. 1 is a front, right, top perspective view of a wine glass holder, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partially enlarged view thereof, taken from FIG. 1;

FIG. 10 is a partially enlarged view thereof, taken from FIG. 2;

FIG. 11 is a partially enlarged view thereof, taken from FIG. 3; and,

FIG. 12 is a partially enlarged view thereof, taken from FIG. 5.

The dashed broken lines in the figures are for the purposes of illustrating portions of the wine glass holder and form no part of the claimed design.

The dash-dot-dash broken lines in FIGS. 1-3, 5, and 9-12 are included to show partially enlarged views only and form no part of the claimed design.
